(57) **CLAIM**

The ornamental design for a delivery robot, as shown and described.

DESCRIPTION

1. Delivery robot
- 1.1 : Perspective
- 1.2 : Front
- 1.3 : Back
- 1.4 : Left
- 1.5 : Right
- 1.6 : Top
- 1.7 : Bottom
- 1.8 : Reference
- 1.9 : Reference
- 1.10 : Reference

Reproductions 1.8 to 1.10 are reference views showing the state of use in alternative positions.
